US0D1065781S

(12) **United States Design Patent** (10) **Patent No.:** **US D1,065,781 S**
(45) **Date of Patent:** **** Mar. 11, 2025**

(54) **FOOTWEAR**

- (71) Applicant: **Crocs, Inc.**, Broomfield, CO (US)
- (72) Inventors: **Alexander Jacob Mayhew**, Denver, CO (US); **Jie Liu**, Pasadena, CA (US); **Catherine Lam**, New York, NY (US); **Michael Sarantakos**, Portland, OR (US)
- (73) Assignee: **Crocs, Inc.**, Broomfield, CO (US)
- (**) Term: **15 Years**
- (21) Appl. No.: **29/825,378**
- (22) Filed: **Jan. 31, 2022**

CLAIM

The ornamental design for footwear as shown and described.

DESCRIPTION

FIG. 1 is a top perspective view of footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1-7 that are overlaid with a white transparent mask bounded by broken lines represent portions that form no part of the claimed design.

1 Claim, 7 Drawing Sheets
